UNITED STATES PATENT OFFICE.

WILLIAM RUNDLE, OF JOHANNESBURG, TRANSVAAL, SOUTH AFRICA.

RAILWAY-VEHICLE COUPLING.

1,153,577.

Specification of Letters Patent. Patented Sept. 14, 1915.

Application filed September 17, 1910. Serial No. 582,538.

To all whom it may concern:

Be it known that I, WILLIAM RUNDLE, a subject of the King of Great Britain, and resident of Johannesburg, Transvaal, South Africa, have invented certain new and useful Improvements in Railway-Vehicle Couplings, of which the following is a specification.

This invention relates to couplings for 10 railway vehicles, and in particular to an automatic coupling, or one which will operate unaided to couple the vehicles when they come into contact, and in which the uncoupling thereof can be effected from the 15 side of the vehicles or without passing in between them.

An important feature of my improved coupling is that it is so constructed that the automatic coupling of the vehicles can 20 take place even though the couplings are fixed within a comparatively large range at different heights.

The invention will be fully described by aid of the accompanying drawing, in 25 which—

Figure 1 is a side elevation of the combined coupler head and coupling. Fig. 2 is a plan view of the structure shown in Fig. 1. Fig. 3 is a front elevation of the structure 30 shown in Fig. 1. Fig. 4 is a cross section of the structure shown in Fig. 1 on line $x-x$. Fig. 5 is a plan view of the link engaging member, detached. Fig. 6 is an elevation of the link engaging member as seen from the 35 inside. Fig. 7 is a plan view of the link engaging member as seen from the underside. Fig. 8 is a side elevation of the counterbalance weight. Fig. 9 is an end elevation of Fig. 8. Fig. 10 is a side elevation of 40 the locking pin for the link engaging member. Fig. 11 is a side elevation of Fig. 10. Fig. 12 illustrates a modified form of the link or coupling member constructed at one end for use with my improved coupling, and 45 at the other end for connecting with any ordinary link coupling. Fig. 13 is a horizontal section of the structure shown in Fig. 1, on line $y-y$, and Fig. 14 is a sectional elevation of a portion of the vehicle illustrating 50 the mode of fixing the coupling thereto.

In the drawings 1 represents a coupler head which may be made of circular, (as shown) or other suitable shape. The coupler head 1 is fashioned at the back with a 55 part 2 of rectangular or other suitable section by means of which the coupler head and

coupling are yieldingly supported in the ordinary casting or bracket 2^a or its equivalent provided on the end of the under-frame 2^b of the vehicle, or in any other suitable position. The end of part 2 serves as a stop for the ordinary collar 2^c which works against a spiral spring 2^d placed around the screw-threaded extension 3 of said part 2 and between said collar 2^c and a plate 3^a fixed between the two members 2^b of the under-frame by means of the pieces 3^b. Extension 3 projects through a hole 3^c in plate 3^a, and on the threaded extremity thereof is screwed the usual nut 4 for fixing the coupler head 70 and coupling to the under-frame—see more particularly Fig. 14.

The numerals 4^a, 4^b, 4^c in Fig. 14 represent the bottom, end and side of the car, and the dotted line 5 in Figs. 1, 2 and 13 represents the end of the car.

The coupler head 1 is constructed with a flared or bell-mouthed opening or recess 6 extending rearwardly into the coupler head for a suitable distance, and at one side with 80 an opening 7 communicating with said recess in which is pivoted a member 8 which constitutes the part which is engaged by one end of the link or coupling bar 9 when the latter is projected into the recess 6. The 85 coupler head 1 is also constructed at the top with a slot or opening 10 in which works a portion of a counterbalance weight 11 which serves for maintaining the link or coupling bar 9 in a more or less horizontal and central position. The coupler head 1 is constructed at the top and at the sides of the opening 10 with lugs or projections 12, 13, which support a pin 14 which forms the 90 pivot for the counterbalance weight 11. 95 Coupler head 1 is also constructed at the top and on the open side with an extension or projection 15 in which is formed a hole 16 for the reception of a pin 17 which serves for locking the member 8 when it is in engagement with the link or coupling bar 9.

The part 8, which as previously stated constitutes the engaging member for the end of the coupling bar 9, is pivoted in the opening 7 or open side of the coupler head by means of a vertical pin 18 which passes through holes in horizontal extensions or lateral enlargements 19, 20 at the top and bottom of the coupler head 1 on the open side.

The shape of the part or member 8 is clearly illustrated in Figs. 5, 6 and 7. Part

or member 8 is fashioned on the inside of the coupler head with a projection 21 which is adapted to engage recess 22 provided near the end of the link or coupling bar 9. This projection 21 is, as shown more particularly in Figs. 5, 6 and 7, rounded both back and front, preferably slightly more at the back than the front, to permit of the movement in either an upward or downward direction of the link or coupling bar 9. The recess 22 in the side of the link or coupling bar 9 with which the aforesaid projection 21 engages is also rounded on the one side as is indicated in Figs. 1, 2 and 12.

The link or coupling bar 9 is constructed the same at both ends when the vehicles to be coupled are provided with my improved coupling. Links or coupling bars can be provided constructed as shown in Fig. 12 at the one end of the special shape above described for my new coupling, and at the other end in the form of an ordinary link for connecting with any ordinary link coupling. The end of the link or coupling bar 9 is, as shown in Figs. 1, 2, 3 and 12, tapered or beveled in a forward direction at the top, bottom and sides, so as to enter the recess 6 in the coupler head the more readily, the beveled surfaces of the coupling bar and the flared opening 6 in the coupler head serving to guide the bar 9 into the position in which it engages the link engaging member.

When the coupling bars are constructed at both ends for use with my improved coupling then the recesses 22 engaging the projections 21 on the members 8 will usually be formed in opposite sides of said coupling bar. As shown in the drawings the coupling bar may be necked or reduced as indicated at 23 between the recesses 22. The ends of the bar are also preferably rounded as indicated at 24 in Fig. 12, as well as tapered or beveled as previously explained, to facilitate their entrance into the coupler heads.

Member 8—see Figs. 5, 6 and 7—is constructed with a recess 25 which when projection 21 on member 8 is in engagement with the recess 22 in the coupling bar 9 coincides with the hole 16 for the locking pin 17. Recess 25—see Fig. 5—is beveled on one side as indicated at 26 to correspond to the locking pin 17 (which is also tapered or beveled on one side as indicated at 27 in Fig. 11) and to facilitate the engagement of said locking pin 17 with the recess 25. The member 8 is shaped or cut away at the bottom as indicated in Figs. 5, 6, and 7 to form shoulders 28, 29 which, by engaging the side of the coupler-head at 30 limit the inward and outward movement of member 8. The outside of the coupler-head at 30 serves, by engaging the shoulder 28, to act as a stop for the member 8 in one direction and the inside of the coupler head at 30 serves, by en-

gaging shoulder 29, as a stop in the other direction. The member 8 is also shaped or cut away at the top as indicated at 31 so as to permit it to rotate to the desired extent when pin 17 is raised out of recess 25, thereby reducing the extent of the vertical movement requisite to disengage pin 17 from said member 8. The shaping or cutting away of the member 8 at the top also forms upon it a shoulder 32 similar to the shoulder 29 on the bottom, which shoulder 32 operates like shoulder 29 to limit the movement of the member 8 in the one direction by engaging the inside of the coupler head at 33.

As indicated at 34 in Figs. 5 and 7 the surfaces formed by cutting away the top and bottom of member 8 are rounded, and the parts of the coupler head at 30, 33 are rounded on the inside where said parts contact with the rounded surfaces 34 to facilitate the movement of member 8 about its pin 18.

The member 8 at the inner top corner—see Figs. 5, 6 and 13—is beveled off as indicated at 35 to facilitate its engagement by a projection 36 which is formed on the counterweight 11 and works in the slot or opening 10 in the top of the coupler head 1. The projection 36—see Figs. 8 and 9—is also beveled or rounded as indicated at 37 on the side which engages member 8 at 35.

The counterweight 11 as previously explained is free to move about the pin 14 which is carried by the lugs 12, 13 formed on the top of the coupler head at the sides of said aperture 10. The projection 36 on the counterweight 11 operates by engaging member 8 on the inside of the coupler head to prevent rotary movement of said member 8—which would result in its disengaging the coupling bar 9. The projection 36 rests upon or engages the top of the coupling bar 9 when the latter is in its coupling position or in engagement with member 8. The projection 36, as indicated at 38 in Fig. 8, is rounded on that face which engages the top of the coupling bar 9 and the weight 11 operating through said projection 36 serves to maintain the coupling bar 9 in a substantially horizontal position when said bar 9 is in engagement with member 8. The projection 36 is approximately equal to the width of the slot 10 in the top of the coupler head 1, and the shoulders 39 formed at the sides of said projection 36 serve as stops to limit the inward movement of said projection.

The counterweight 11 as shown in Figs. 1, 2 and 8 is constructed on the underside with a curved recess 40 with which a rod or spindle 41 engages. The rod or spindle 41 also engages in a hole 42 formed in the upper end of the locking pin 17.

On the rod or spindle 41 and between the counterweight 11 and locking pin 17 is ar-

ranged one end of a link 43, the link loosely encircling the rod or spindle. The link 43 is attached to the end of a crank 44 provided on a spindle 45 carried by suitably positioned brackets 46 fixed on the end of the vehicle. The spindle 45 extends in a horizontal direction to the side of the vehicle and is provided with a handle 47 for rotating it in order to lift the counterweight 11 10 and at the same time withdraw the locking pin 17 from engagement with the member 8. Link 43 is constructed with an elongated slot 48 to provide for any desired adjustment of the parts, and the pin 17 is suitably 15 shaped to allow for the movement thereof in the hole 16 when it is lifted to disengage slot 25.

The numeral 49 represents a link or its equivalent fixed to the back of the vehicle 20 in such a position that the handle 47 can be placed in engagement with it to maintain the locking pin 17 and counterweight 11 in their disengaging positions. The projection 36 operates to retain member 8 in its 25 engaging position with the coupling bar 9 until the counterweight 11 is raised by the handle 47.

Copies of this patent may be obtained for five cents each, by addressing the "Commissioner of Patents, Washington, D. C."

What I claim as my invention and desire to protect by Letters Patent is:—

In a coupling for railway vehicles, in combination, a coupler head, a coupling bar, an engaging member pivoted to the coupler head for engaging said coupling bar, a counterbalance weight which yieldingly maintains the bar in position, a pin for locking the engaging member when it is in engagement with the bar, and means for simultaneously disengaging the locking pin from the engaging member and the weight from the coupling bar, said means comprising a rod 30 or spindle which engages in a curved recess formed in the underside of the counterweight and in a hole formed in the upper end of the locking pin, and a link loosely 35 encircling the rod or spindle between the counterweight and locking pin.

In testimony whereof I have signed my name to this specification in the presence of two subscribing witnesses.

WILLIAM RUNDLE.
